UNITED STATES PATENT OFFICE.

FRANK J. SINGER, OF DETROIT, MICHIGAN, ASSIGNOR TO AMERICAN PRESSWELD RADIATOR CORPORATION, OF DETROIT, MICHIGAN, A CORPORATION OF DELAWARE.

RADIATOR-COUPING.

1,230,812.

Specification of Letters Patent. Patented June 19, 1917.

Application filed January 26, 1916. Serial No. 74,294.

To all whom it may concern:

Be it known that I, FRANK J. SINGER, a citizen of the United States, residing at Detroit, in the county of Wayne and State 5 of Michigan, have invented a new and useful Radiator-Coupling, of which the following is a specification.

Joints between adjacent sections of pressed sheet metal radiators as heretofore formed have usually been of two forms: either an interlocking seam has been used or a fused joint. The first mentioned variety has proven unsuited to the varying conditions of temperature and moisture, and 15 is of high initial expense; and the fused joints have failed because a complete and uniform fusion of the metal was not uniformly secured throughout the seam.

The present invention relates to a radiator coupling in which a perfect fusion is easily and quickly secured between the metal of the adjacent radiator section and the corresponding member of the coupling, and wherein the coupling members, when there- 25 after connected by a suitable nipple, may be brought into close relation to each other to form a tight and neat joint.

One embodiment of the invention is shown in the drawings, Figure 1 being a fragmentary horizontal section through the radiator at the level of the coupling, Fig. 2 a fragmentary end view looking from the right hand side of Fig. 1, Fig. 3 a fragmentary vertical section showing the manner 35 of attaching the plug receiving element, and Fig. 4 a longitudinal section of a pressed sheet metal connecting nipple which it is preferred to use.

The thin pressed sheet metal half sections 40 1 of the radiator, of any approved shape, are provided with out-turned annular flanges 2, and are connected together at 3 in any desired manner, preferably by fusion. Received within each of the flanges 2 is an 45 interiorly threaded coupling member 4 or 5, as the case may be, that projects into the section and is provided with the annular strengthening flange 6 that is faced at 8 and has formed therein an annular groove 9. The latter is removed inwardly from the 50 outer circumferential surface of the flange 6 a distance substantially equal to the thickness of the flange 2 to form an annular flange 10 concentric with the latter, and is 55 of a depth sufficient to make, when fused,

a welded joint of the required width. As a result, heat from a blow pipe or an electric arc, when applied to the parts, fuses both flanges at the same time, whereas, were the groove 9 omitted, fusion of the flange 2 60 would precede that of the adjoining portion of the coupling member, and by the time the latter had reached a fusing temperature, the former would, in many instances, have become partly burned or weak- 65 ened.

It is preferred to taper the inwardly projecting end of the coupling member as shown at 11, whereby any liquid of condensation is caused to cling to and flow down 70 the side of the section rather than drip, thus avoiding undesirable noise.

The material may be removed at 12 along the inner edge of the face 8 to allow easy entrance of the nipple 13. The latter is 75 preferably formed of pressed metal and has the short lugs 14 pressed inwardly therefrom, preferably at points diametrically opposite each other, previous to the operation whereby the usual right and left hand 80 threads are formed. These lugs serve a double purpose in that they may be used not only to apply a wrench or tool for screwing the sections together but also for the purpose of holding the nipple in proper 85 rotative relation to the dies by which it is threaded. Since the lugs are located in the position shown, it follows that they do not interfere with the formation of a tight joint.

When the nipples are fully screwed up, 90 the faces 8 engage with each other and the edges of the welded seams are in close relation to one another, which both tends to prevent leakage and insures a neat appearance.

The end section of the radiator may be formed as shown in Fig. 3, from which it will be seen that the threaded coupling or reinforcing member 16 for receiving the plug 17 is provided with the annular rib 100 or flange portion 18 of thickness substantially equal to that of the adjacent sheet metal. Simultaneous fusion of the parts therefore takes place as described with reference to the members 4.

It is clear that many changes may be made in the details of construction without departing from the spirit of my invention; also that sections of containers other than radiators may be joined in the same way.

I do not, therefore, wish to be limited otherwise than as indicated by the subjoined claims.

I claim:—

- 5 1. A container comprising a plurality of sections each formed of thin sheet metal and each having one of its walls formed with an outwardly extending tubular flange, each section having an internally threaded coupling member of greater thickness than the flange secured to the latter by welding, said coupling members each including a flange or rib concentric with, adjacent to and of substantially the same thickness as the first 10 mentioned flange whereby a proper fusion of the metal of the two flanges may be obtained, a nipple threaded into the coupling members, the latter being drawn toward each other by the nipple until pressure from 15 one is transmitted to the other over the outer faces thereof.
- 20 2. A radiator comprising a sheet metal section having one of its walls formed with an outwardly extending annular flange, an internally threaded coupling member secured to said flange, said coupling member extending out into the section beyond the inner face thereof and being tapered, whereby dripping of water of condensation is 25 avoided.
- 30 3. A radiator comprising a sheet metal section having one of its walls formed with an outwardly extending annular flange, an internally threaded member secured to said flange, an externally threaded member screwed into said internally threaded member, said internally threaded member extending out into the section beyond the inner face thereof and being tapered, whereby 35 dripping of water of condensation is avoided.
- 40 4. A radiator comprising a section having an opening in one of its walls, an internally threaded member rigidly secured in said opening, an externally threaded member 45 screwed into said internally threaded member, said internally threaded member extending out into the section beyond the inner face thereof and being tapered, whereby dripping of water of condensation is 50 avoided.
5. A radiator comprising a sheet metal section having one of its walls formed with an outwardly extending annular flange, an internally threaded coupling member welded to said flange, said coupling member extending out into the section beyond the inner face thereof and being tapered, whereby dripping of water of condensation is 55 avoided.
6. A sectional container comprising a sheet metal section having an opening therein, an internally threaded coupling member secured to the wall of the opening, a nipple threaded into the coupling member, said nipple having short lugs pressed inwardly 60 from an intermediate point in its length and being of substantially the same thickness at the lugs as at points adjacent thereto, whereby force may be applied to screw the nipple 65 into the coupling member.
7. A sectional container comprising a plurality of sheet metal sections having aligned openings formed therein, internally threaded coupling members secured, respectively, to the walls of the openings, the threads on one of the members being right handed and those on the other being left handed, and a seamless nipple having right and left hand threads that engage, respectively, with the corresponding threads on 70 the coupling members, said nipple having short lugs pressed inwardly therefrom at an intermediate point in its length prior to the formation of the threads thereon, whereby force may be applied to screw the nipple 75 into the coupling members.
8. A radiator comprising a sheet metal section having an opening therein, an internally threaded coupling member secured to the wall of the opening, a nipple threaded 80 into the coupling member, said nipple having a lug extending inwardly from its inner surface and being of substantially the same thickness at the lug as at points adjacent thereto, whereby force may be applied to screw the nipple 85 into the coupling member.

In testimony whereof I sign this specification.

FRANK J. SINGER.
